UNITED STATES PATENT OFFICE.

GEORGE T. TRUNDEL, OF CLEVELAND, OHIO, ASSIGNOR TO THE AMERICAN MULTOGRAPH COMPANY, OF CLEVELAND, OHIO, A CORPORATION OF OHIO.

LINOTYPE CASTING MECHANISM.

1,122,819.

Specification of Letters Patent.

Patented Dec. 29, 1914.

Application filed July 14, 1913. Serial No. 778,876.

To all whom it may concern:

Be it known that I, GEORGE T. TRUNDEL, a citizen of the United States, residing at Cleveland, in the county of Cuyahoga and 5 State of Ohio, have invented a certain new and useful Improvement in Linotype Casting Mechanism, of which the following is a full, clear, and exact description, reference being had to the accompanying drawings.

10 The object of this invention is to provide an effective mechanism for forming linotype slugs of small height and grooved on their opposite sides. Such slugs may conveniently carry the characters of an address 15 and be mounted in slots in a plate, whereby a simple and effective address plate is provided. Slugs may also be mounted in a printing device having rails with overhanging edges, like the commercial multigraph, 20 or in a flexible blanket formed of rails, like the flexotype.

My mechanism is adapted to use with the ordinary Mergenthaler machine, which assembles matrices. The mechanism comprises a suitable separable mold mounted 25 on a mold wheel of the Mergenthaler machine, combined with suitable mechanism for automatically opening and closing the mold, thus enabling the slugs with the opposite grooves and the projecting feet to be cast and thereafter freed from the mold. After being discharged, it is only necessary 30 to break off or otherwise remove the jet or base portion of the slug to leave the finished 35 product.

My invention is hereinafter more fully explained and its essential characteristics are set out in the claims.

In the drawings, Figure 1 is a front elevation of a mold wheel equipped with my mold and operating mechanism; Fig. 2 is a vertical central cross section of the mold wheel, mold and coöperating parts; Fig. 3 is a partial edge view of the mold wheel and 40 the mechanism carried thereby; Fig. 4 is a perspective view of the finished line slug.

Referring by numerals to the parts shown in the drawing, 1 indicates a mold wheel having a hub 2 by which it is journaled in 45 the bearing 3. The wheel is held in its

bearing by a stationary stud 4 occupying the hub 2 and having a head 5 seating in a circular recess in the wheel, the stud, at its other end, being suitably locked to the bearing. As shown, this locking is accomplished 55 by a key 6 between the stud and bearing and a nut 7 screwing onto the threaded end of the stud. The wheel is shown as having gear teeth 8 at its periphery, by which it may be rotated in the usual manner. It is 60 also provided with the usual Mergenthaler centering studs 9.

Mounted in a chordal slot in the wheel is a box 10 having a prismatic slot 11 through it of proper dimensions and form to constitute a mold for the base or jet portion of the slug. The sides of this mold are substantially parallel with each other, but, if desired, may be slightly tapered toward the inner side of the wheel. The box 10 is 70 shown as made of separate side members 12 and end members 13. The side members have flanges 14 through which pass screws 15 into the wheel. The end pieces may be driven into place, or otherwise held. The 75 box members project beyond the outer face of the wheel, and each side member has a flange 16 which leaves a groove between it and the face of the wheel.

Mounted on the face of the wheel are two 80 blocks 20 and 21. These blocks are held near their adjacent edges against the face of the wheel by having flanges 22 extending into the grooves of the members 12, the blocks having grooves outside of these 85 flanges to receive the flanges 16. Near their outer edges the blocks 20 and 21 are held by small T-shaped blocks 26, secured by screws 25 to the face of the wheel, and overhanging ribs 27 on the blocks 20 and 21. 90 The construction described holds the blocks 20 and 21 snugly against the face of the mold wheel while allowing them to be moved toward or from each other. Mechanism for causing such movement will be 95 hereinafter described.

The blocks 20 and 21 overhang the outer face of the box 10, as clearly shown in Fig. 2, and such overhanging portions are provided with beveled edges 30 adjacent to the 100

box, and then with grooves 31, and, at their outer faces, with rabbets 32. There remain ribs between the grooves and rabbets which project toward each other into the mold space. Accordingly, when the blocks are nearly together, there is provided a mold space which contracts from the width of the main sprue space toward an intermediate line and then spreads into a mold space having approximately the cross section of the letter I. Accordingly, the box and the two blocks coöperate to provide a mold for casting a line slug of the form desired, with the base or jet portion connected therewith by a narrow neck.

Fig. 2 shows, at 40, matrices having in their edges, intaglio characters 41 to form the characters on the cast slug. These matrices may be of the usual Mergenthaler form 20 and are held in the usual box 43 against the outer face of the blocks 20 and 21. A groove 44 in the block 21 enables the matrices to occupy a raised position to present a second set of characters. Coöoperating with the inner face of the box 10 is the spout 45 of a suitable melting pot 46.

The parts described coöperate to enable the casting in the mold space of a slug of the form shown at A in Fig. 2. After such 30 slug is cast, it is only necessary to remove it from the mold and separate, by breaking or otherwise, the base portion of the slug to leave the finished slug shown at A¹ in Fig. 4.

To enable the removal of the cast slug, I 35 provide mechanism for automatically separating the mold blocks 20 and 21 as the wheel 1 revolves after the casting of the slug. The mechanism shown for this purpose comprises a pair of levers 50 (Figs. 1 40 and 3) pivoted at 51 to the mold wheel and connected by links 52 and 53 with the blocks 20 and 21, respectively. These links are pivoted to the levers at 54 and 55 and extend in opposite directions, and at their outer 45 ends are pivoted at 56 and 57 to ears 58 and 59 projecting from the ends of the blocks 20 and 21, respectively. Pivoted to the free ends of the levers 50 are links 60, the other ends of which are pivoted by a common 50 pivot 62 to a bar 64. The outer end of this bar is slidably guided radially of the wheel by a pin 65 carried by the bar and having a head which occupies an undercut radial slot 66 in the mold wheel. The inner end 55 of the bar is journaled on a bushing 70 clamped to the head 5 of the central stud by a pin 71 having a head engaging an undercut groove 72 in the head, the other end of the pin being threaded and having a nut 74. The groove 72 is diametric of the head 5. 60 The nut 74 clamps the pin 71 and bushing 70 in stationary but adjustable position on the head. This position, as shown, is eccentric of the mold wheel, wherefore, as the

wheel revolves, the outer end of the bar 64 65 travels in and out, moving the pivot 62 of the links and thereby swinging the levers 50 to move the blocks 20 and 21.

When the mold wheel is in position for casting,—that is, with the blocks 20 and 21 70 in their uppermost position, the pivot pin 62 on the bar 64 has its outermost position, bringing the blocks into their innermost positions, as shown in Fig. 2, where they constitute the mold for the head portion of the 75 slug. After the casting of the slug, the mold wheel starts to revolve, and in this movement the pin 65 slides radially inward in the slot 66, thus pulling on the links 60 and levers 50 and gradually separating the 80 mold blocks 20 and 21. This movement may be sufficient so that when the mold wheel has made a quarter turn, the blocks are separated by a distance as great as the cross section of the mold opening 11, so that the slug 85 may be conveniently shoved out between the blocks by means of a suitable plunger acting outwardly through the inner face of the wheel.

The discharge of the cast slug may be 90 made at any suitable point in the revolution of the mold wheel. I find it convenient to cast the slug when the mold blocks are at the top of their movement and discharge the 95 slug three-quarters of a rotation beyond such point, the blocks simply opening idly farther than necessary to clear the slug and then returning through such idle movement during the lower half of the rotation. Fig. 1 shows, in dotted lines in the lower half of 100 the circle, the mold blocks in this abnormally separated position.

I have shown the links 60 made in a sinuous form, so as to give them a slight spring action, whereby the mold blocks may be 105 forced snugly into their innermost position. This innermost position is limited by the projecting portion of the box members 12.

Having thus described my invention, what 110 I claim is:

1. In a mechanism of the character described, the combination, with a mold wheel and means for holding matrices, of a mold mounted on the wheel and having a movable 115 head-part with oppositely facing ribs extending lengthwise of the mold, whereby a slug having longitudinal grooves on its opposite sides may be cast, and means for separating the said head-part mold to release the 120 cast slug.

2. The combination, with means for holding matrices, of a mold having an immovable body portion, and a movable head portion with inwardly projecting ribs whereby 125 a slug may be cast having longitudinal grooves adjacent to the printing face, and means for separating the head portion to

- allow the body portion to be ejected through the head portion space.
3. The combination of a mold wheel, a mold carried thereby and comprising a body portion mounted stationarily on a wheel and having a prismatic slot, and a head portion mounted on the wheel in a manner enabling separation, said head portion having an inwardly projecting rib, and means for holding matrices against the head portion.
4. The combination, with a movable mold wheel, of a mold carried thereby and comprising a body portion stationarily mounted on the mold wheel, a head portion including two blocks having ribs on their adjacent faces, and mechanism for causing said blocks to separate after the slug is cast.
5. The combination of a mold wheel, a mold carried thereby and comprising a body portion mounted in an opening in the front wall, and a head portion mounted on the face of the mold wheel and separable in opposite directions to release the slug.
6. The combination of a mold wheel having an opening, a mold for the body of the slug mounted in said opening, a mold for the head of the slug including two blocks mounted on the face of the wheel, and means for causing said blocks to approach or recede from each other.
7. The combination of a mold wheel having a slot, a mold for the body portion of the slug mounted in said slot, a pair of blocks providing a mold for the sides of the head portion of the slug, said blocks being movably mounted on the face of the wheel, and mechanism operated by the rotation of the wheel to cause the blocks to move apart.
8. In a device of the character described, the combination of a pair of coöperating mold members, a pair of pivoted levers, links connecting said levers with the respective mold members, and mechanism for concurrently operating said levers.
9. The combination of a mold wheel, a pair of mold members movably mounted thereon, a pair of pivoted levers connected with the respective members, a pair of links for moving said levers, and mechanism for automatically moving the links when the mold wheel revolves.
10. The combination of a mold wheel, a pair of mold members movably mounted thereon, a stationary stud about which the wheel revolves, a bar pivoted to the stud eccentrically of the wheel and slidably connected with the wheel, and mechanism connecting said bar with the mold members.
11. The combination of a mold wheel having an opening, a box mounted in said opening and providing a mold for the body portion of the slug, said box having projecting flanges spaced beyond the face of the mold wheel to leave grooves, a pair of movable blocks ribbed to provide a mold for the head portion of the slug, said blocks having flanges occupying said grooves.
12. The combination of a mold for the body portion of the slug, and a pair of co-operating members for molding the head portion of the slug, said members having ribs and adjacent grooves extending lengthwise of the mold and having inclined portions extending from points near the groove to the outer face of the body mold.
13. The combination, with a mold having a prismatic opening for the body portion of a slug, and two relatively movable members grooved and ribbed lengthwise of the mold, and means for holding them with such grooved and ribbed portions opposite each other and spaced apart and in line with the opening of the body mold.
14. The combination, with means for holding a line of matrices, of a mold wheel, a body mold carried by the mold wheel, a pair of mold members for the head portion of the slug coöperating at one side with the matrices and at the other with the body mold, said head members being separable to release the cast slug.
15. The combination, with means for holding a line of matrices, of a mold wheel, a body mold carried by the mold wheel, a pair of mold members for the head portion of the slug coöperating at one side with the matrices and at the other with the body mold, and automatic mechanism operating in consequence of the rotation of the mold wheel to separate said head members to enable the cast slug to be ejected.
16. The combination, with means for holding a line of matrices, of a body mold, a pair of mold members for the head portion of the slug coöperating at one side with the matrices and at the other with the body mold, said head members being separable to release the cast slug.
17. The combination, with means for holding a line of matrices, of a body mold, a pair of mold members for the head portion of the slug coöperating at one side with the matrices and at the other with the body mold, and mechanism to separate said head members to enable the cast slug to be ejected.
18. The combination, with means for holding a line of matrices, of a mold having a body portion defining a prismatic slot, and a movable head portion having a longitudinal rib whereby a slug may be cast having a longitudinal groove adjacent to the printing face.
19. The combination of a mold wheel, a mold carried thereby and comprising a body portion consisting of side members and end members mounted in an opening in the wheel, and a head portion comprising two

1
blocks mounted on the face of the mold wheel between the end members and separable to release the slug.

20. The combination of a mold wheel having an opening, a mold for the body of the slug including side members rigidly mounted in said opening, and a mold for the head of the slug including two blocks adapted to

coact with the matrices and movably mounted on the face of the wheel.

In testimony whereof, I hereunto affix my signature in the presence of two witnesses.

GEORGE T. TRUNDE.
